UNITED STATES PATENT OFFICE.

WILLIAM BRENNING, OF SHREVEPORT, LOUISIANA.

TIE-PLATE.

1,092,013.

Specification of Letters Patent. Patented Mar. 31, 1914.

Application filed May 21, 1913. Serial No. 769,052.

To all whom it may concern:

Be it known that I, WILLIAM BRENNING, having taken out papers for citizenship of the United States, residing at Shreveport, 5 in the parish of Caddo and State of Louisiana, have invented new and useful Improvements in Tie-Plates, of which the following is a specification.

The present invention relates to improvements in tie plates for railway rails, and resides in the novel construction, combination and arrangement of parts set forth in the following specification and falling within the scope of the appended claim.

15 In the drawing: Figure 1 is a top plan view of the improvement before the same is applied upon a tie, Fig. 2 is a side elevation of the same, Fig. 3 is a view illustrating the position of the plate when the same is 20 to be secured to the tie, Fig. 4 is a similar view illustrating the device secured to the tie and the fingers thereof engaging with the base flanges of the tie, Fig. 5 is a top plan view of the device illustrated in Fig. 25 4, Fig. 6 is a sectional view on the line 6—6 of Fig. 1, Fig. 7 is a side elevation of the device illustrated in Fig. 3, and Fig. 8 is a sectional view on the line x—x of Fig. 4.

Referring now to the drawing in detail, 30 the numeral 1 designates an ordinary wooden tie, and 2 the rail which is adapted to be arranged upon my improved tie plate, which is designated broadly by the numeral 3. The plate is adapted to be secured upon 35 the tie 1 and to be attached to the rail 2 without the employment of means not connected with the plate. The tie plate is constructed from a single piece of flat metal and embodies a body 4 having sides 5. The 40 sides have their edges inclined toward each other and are thus substantially V-shaped. The apex of the sides or the lower portions thereof are formed with V-shaped teeth 6. The teeth 6 are adapted to be bent at a right 45 angle to the sides 5, when the device is to be applied to the ties, and as illustrated in Fig. 3 of the drawing. The sides 5 are bent at an angle from the body 4 at points, designated by the numeral 7, in Fig. 1 of the 50 drawings. The body, provided adjacent its opposite longitudinal edges with a plurality of inwardly extending substantially V-shaped slotted portions, the metal between the same being bent upwardly to provide

fingers 8, while the said body between the 55 spaces provided for the fingers 9 are further slotted to form the plate with downturned substantially V-shaped prongs 9. By reference to Fig. 3, it will be noted that the sides 5 are bent from the portion 7 at an 60 angle greater than a right angle, so that the body may be snugly fitted upon the upper face of the tie and the prongs 9 embedded within the said tie. The teeth 6 are also arranged at an angle to the sides of 65 the tie and when forced to within the tie will exert a pressure or tension upon the top of the plate to draw the said top more tightly into engagement with the tie. When the plate is thus positioned, the rail 2 is 70 arranged between the fingers 8 and the said fingers are forced over the base flanges of the tie as clearly illustrated in Figs. 4, 5 and 8 of the drawings.

From the above description, taken in connection with the accompanying drawing, the simplicity of the device, as well as the advantages thereof will, it is thought, be perfectly apparent to those skilled in the art to which such invention appertains without further detailed description.

Having thus described the invention, what I claim is:

A tie plate formed from a sheet of bendable material including a body having integrally formed upwardly extending fingers, the said body between the fingers being provided with downwardly extending prongs, bendable sides for the body, said sides having their edges provided with teeth 85 which are adapted to be bent at a right angle to the sides, the prongs of the teeth adapted to be inserted within the top of the tie, the sides bent over the tie to retain the teeth at an angle to the sides of 90 the tie to permit of the said teeth when forced within the sides of the tie exerting a downward pressure upon the top of the plate, and the fingers of the plate adapted to be bent over the base flanges of a rail which 95 is adapted to be arranged upon the plate.

In testimony whereof I affix my signature in presence of two witnesses.

WILLIAM BRENNING.
